UNITED STATES PATENT OFFICE

NILS D. LEVIN, OF COLUMBUS, OHIO, ASSIGNOR TO THE JEFFREY MANUFACTURING COMPANY, OF COLUMBUS, OHIO, A CORPORATION OF OHIO

ELECTRIC SWITCH

Application filed August 3, 1926. Serial No. 126,846.

The present invention relates to certain new and useful improvements in electric switches of the type which is provided with means to localize and minimize the effect of 5 the arcs formed between the contact members of the switch when the current is interrupted.

The especial object is to provide a switch of the class described having large carrying capacity and wherein the arcing caused by 10 the interruption of the current is localized to points not included in the circuit during the maintenance of said circuit.

A further object is to provide in a switch of the class described, improved means to 15 minimize the destructive effect of the arc upon the contact elements of the switch.

These and other objects will be fully set forth in the following specification and illustrated in the accompanying drawings of 20 which

Fig. 1, is a plan view of a switch mechanism constructed in accordance with my present invention, certain parts being broken away to reveal other parts.

25 Fig. 2, is a sectional view taken along the lines II—II of Fig. 1.

Like numerals refer to similar parts in both figures.

In application, Serial No. 105,873, filed 30 April 30, 1926, by Walter J. Bauroth, there is disclosed an explosion proof casing adapted to protect electrical apparatus subject to the production of electric arcs from contact with the explosive gas charged atmosphere of a 35 coal mine. For purposes of illustration I have here shown a casing such as above described, in which is mounted two electric switches constructed in accordance with my present invention, operatively connected with

40 the locking lever of said casing, and electrically connected with the conductors of an electric circuit, in such manner that when the casing is open for inspection or adjustment of its contents, both sides of said circuit will 45 be disconnected from the source of electric supply, and said circuit may not be restored until the casing is closed and its cover locked in closed position.

As shown in the drawings the numeral 1 50 refers to the casing and the numeral 2 re-

fers to the disc by which the opening in the top of the casing may be closed. The disc 2 is pivotally attached to the hinge member 3 by the pivot pin 4, and the hinge member 3 is rotatable about a hinge pin 5 which is attached to the side wall of the casing by the lug 6. The slot 7 in the hinge member 3 allows sufficient movement of the hinge member 3 transversely of the hinge pin 5 to permit the disc 2 to be moved 55 directly outwardly of the casing by the screwing action when said disc is rotated about the pivot pin 4. The locking levers 8 are pivotally mounted in suitable bearings formed in the end wall of the casing, and 60 these levers are joined together by a cross bar 9 on which is mounted a roller adapted to engage the hinge member 3 when the levers 8 are in their locked position, to thereby prevent the outward movement of said hinge 65 member and the attached cover disc 2. In like manner the engagement of the roller 10 with the hinge member 3 will prevent movement of the locking levers 8 to their extreme 70 forward, or locked position, until the cover 75 disc 2 has been screwed home to its closed position.

Mounted within the casing 1 is an insulating base 11 upon which are mounted the electrical devices contained within the casing. 80 Attached to the insulating base 11 are the switches 12 and 13 positioned adjacent the ends of the casing, and each operatively connected with, but electrically insulated from the adjacent locking lever 8. As these 85 switches are alike a description of one will apply to both.

Fixed to the insulating base 11 is a metallic supporting member 14 connected in suitable manner through the conductor 15 with 90 the source of electric supply. Formed in the supporting member 14 in alinement with the axis of the journal of the locking lever 8 is a journal bearing in which is mounted a hub 16 having radially extending arms 17 95 and 18 to the extremities of which are attached contact segments 19 and 20 adapted to engage with the contact brushes 21 and 22 respectively. The brushes 21 and 22 are fixed to a supporting member 23 mounted 100

upon the insulating base 11, and electrically connected with the electric apparatus which is to be supplied with current through the conductor 24. The proportions of these parts are such that when the locking lever 8 is in its extreme forward, or locking position, both of the contact segments 19 and 20 will be in contact with their respective brushes 21 and 22, and when the locking lever 8 is in its rearward, or open position, neither of these contact segments will engage either of said brushes. In order to localize the destructive effect of the electric arcs upon the contact segments to parts not included in the circuit when the switch is fully closed, I have extended the contact segment 19 rearwardly of the supporting arm so as to maintain connection with the brush 21 until after the connection is broken between the segment 20 and the brush 22. By this arrangement no arc is formed on the segment 20 and the arc formed on the segment 19 is removed from that part of the segment in contact with the brush 21 when the switch is fully closed. To further minimize the destructive effect of the electric arc I have mounted adjacent the brush 21 a permanent horseshoe shaped magnet 25, the poles of which extend into proximity with said contact brush 19 so as to maintain a magnetic field at the point where the circuit is finally broken. The magnetic field produced by this permanent magnet tends to quickly extinguish the electric arc and thereby reduce its injurious effect upon the contact segment 22.

It is to be understood that the devices above described may be subjected to a wide variation as to detail without departure from the spirit of my invention.

What I claim is:

1. In a switch, a pair of spaced segmental contact elements, means supporting said elements for rotary movement about a common axis, a brush arranged tangentially to the path of each of said contact elements for cooperation with said elements, a conductor in connection with said contact elements, a conductor in connection with said brushes, and means to rotate said contact elements to bring them into and out of contact with said brushes, one of said contact elements having an extension arranged to make contact first and to break contact last.

2. In a switch, a pair of spaced segmental contact elements, means supporting said elements for rotary movement about a common axis, a brush arranged tangentially to the path of each of said contact elements for cooperation with said elements, a conductor in connection with said contact elements, a conductor in connection with said brushes, and means to rotate said contact elements to bring them into and out of contact with said brushes, one of said contact elements having an extension arranged to make contact first

and to break contact last, the respective conductor being connected with said last named contact element at the supported portion of the latter.

3. In a switch, a pair of spaced segmental contact elements, radial arms supporting said elements for rotary movement about a common axis, a brush arranged tangentially to the path of each of said contact elements for cooperation with said elements, a conductor in connection with said contact elements, a conductor in connection with said brushes, and means to rotate said contact elements to bring them into and out of contact with said brushes, one of said contact elements having an extension arranged to make contact first and to break contact last. 70

4. In a switch, a pair of spaced segmental contact elements, radial arms supporting said elements in constant relation to each other for rotary movement about a common axis, a brush arranged tangentially to the path of each of said contact elements for cooperation with said elements, a conductor in connection with said contact elements, a conductor in connection with said brushes, and means to rotate said contact elements to bring them into and out of contact with said brushes, one of said contact elements having an extension arranged to make contact first 80

and to break contact last. 90

5. In a switch, a pair of spaced segmental contact elements, integral radial arms supporting said elements in constant relation to each other for rotary movement about a common axis, a brush arranged tangentially to the path of each of said contact elements for cooperation with said elements, a conductor in connection with said contact elements, a conductor in connection with said brushes, and means to rotate said contact elements to bring them into and out of contact with said brushes, one of said contact elements having an extension arranged to make contact first 100

and to break contact last. 105

6. In a switch, a pair of spaced segmental contact elements, radial electrically-conductive arms supporting said elements for rotary movement about a common axis, a brush arranged tangentially to the path of each of said contact elements for cooperation with the latter, a conductor in connection with said contact elements through said arms, a conductor in connection with said brushes, and means to rotate said contact elements to bring them into and out of contact with said brushes, one of said contact elements having an extension arranged to make contact first 115

and to break contact last. 120

7. In a switch, a pair of spaced segmental contact elements arranged one before the other, radial electrically-conductive arms supporting said elements in constant relation for rotary movement about a common axis, a brush arranged tangentially to the path of 125

130

each of said contact elements for cooperation with the latter, a conductor in connection with said contact elements through said arms, a conductor in connection with said brushes, and means to rotate said contact elements to bring them into and out of contact with said brushes, one of said contact elements having an extension arranged to make contact first and to break contact last.

10 In testimony whereof I have hereunto set my hand.
